corporation of Delaware

Application March 2, 1943, Serial No. 477,752

4 Claims. (Cl. 20—101)

1

The present invention relates to the placement of particles of thermal insulating material to build up a thermally insulating integrated mass of such material in a confined space. In particular it relates to carrying the material in a gaseous vehicle (hereinafter referred to as air) to a deposited growing mass of such particles formed by deposition of particles from the vehicle.

In its general aspect the invention contemplates completely confining a space to be so filled with insulation material, whereby to define the form of the mass to be produced. The space may be provided substantially completely, by or within existing articles. However, as required or desired for the purposes of the invention, the space to be filled is completely defined by bounding facial walls having essentially some filtering area for exhausting the gas in which particles of the insulating material are introduced, and having essentially in the area of the confining walls, one or more inlet areas for introducing the gas containing the particles, each such inlet area being essentially in and a fraction of a confining wall or face in a manner analogous to the relation of the area of a pouring sprue in molds for casting metal articles to a space-defining area of the mold.

It is also a general aspect of the invention that the particles of insulating material are such as may be consolidated into a gas-filtering body, when in finally deposited form, whereby in conducting and completing the introduction, gas entering the space through inlet area may pass through all or a part of the body as required to exhaust through filtering area.

Another general aspect of the invention permits the form of the space to be complex, or angular, and not limited to panel-form spaces. Thus, the vehicular stream of gas is introduced at a differential pressure, relative to the pressures at inlet area and at filtering area, and at such a velocity that the particles suspended in the gas are carried with turbulence inside the space to all portions of the space remote from inlet area, and that the differential pressure packs the deposited mass to a consolidated body filling the space while said pressure of the gas stream is maintained to and, if desired, even after the complete filling of the space.

The invention is applicable in many fields, for example, in packing fiber or other insulating material into carboys to protect and insulate the flasks of liquid therein. However, its presently preferred use is in insulating the doors and cabinets of refrigerators, such as are used in homes.

In the field of artificial refrigeration, high standards for insulation in domestic and other refrigerators have developed in order to minimize heat loss, because high heat loss adds to the cost of operation. Considerable difficulty has

2

been encountered in the commercial development of refrigerator insulation in parallel with the development of domestic artificial refrigeration. Along with high standards and for low heat loss, low cost of insulating material and of insulating process are important, as are uniformity in each cabinet, and uniformity from cabinet to cabinet in a production line.

In addition, there is the problem of permanence, in which resistance to settling of packed bulk insulation is most important. Such resistance can be attained by increasing the density of packing, with which heat leak or heat conductance increases, as a general rule, in the ranges encountered in refrigerators. It is, therefore, important to minimize density, consistently with acceptable resistance to settling and acceptable insulating value. All these factors lead to a need for a process which is subject to control for meeting them.

In the prior art there has been no low-cost process for packing a specified material uniformly and integrally into a cabinet, and uniformly from cabinet to cabinet in a production line. The present invention provides such a process, and so used it gives reproducible results with any reproducible material. Vegetable fibers such as from wood may readily be produced from time to time with reproducible properties within given specifications, and with such material and with the present invention, a low-cost process for uniformly and efficiently insulating spaces, such as those in refrigerators, becomes available to the manufacturers of refrigerators. Reference is made to my copending application Serial No. 336,495, filed May 22, 1940, now Patent No. 2,325,056, issued July 7, 1943, describing reproducible fibers, which are useful as particles for practice of the present invention.

The present invention is a continuation-in-part of my prior application Serial No. 294,212, filed September 9, 1939, wherein the principles of the process are disclosed, which application is generic to the present application. The present application is a companion to Serial No. 477,751, and Serial No. 477,755, each filed March 2, 1943, as a continuation-in-part of said parent application Serial No. 294,212. In Serial No. 294,212 the invention being claimed is generic to the inventions being claimed in said Serial No. 477,751, in Serial No. 477,755, and in the present application. The invention being claimed in said application Serial No. 477,751 is generic to the inventions being claimed in the present application and in Serial No. 477,755. The invention being claimed in the present application is generic to the invention being claimed in Serial No. 477,755.

It is an object of the present invention to fill a space confined in part by bounding facial walls providing an opening, such as the space in an

open-topped box containing a body and providing an opening through which the body may or may not project, and confined in remaining part by closure means for said opening, said closure having inlet area for introducing a stream of gas containing suspended particles of insulating material, and having also filtering area for exhausting said gas.

It is a particular object of the invention to provide such a confined space that it may have a region thereof remote from an inlet area, with obstructing wall area in the direct line between said region and said inlet area, whereby insulating particles are carried around the said obstruction in filling the space.

It is a particular object of the invention to fill the space provided for insulation in refrigerator cabinets in which a food compartment is already mounted, by employing a fixture closure for open area lying between the cabinet and compartment in the vicinity of the door opening which gives access to the food compartment through the cabinet, said closure having inlet area for introducing a stream of gas containing insulating particles, and having also filtering area for exhausting said gas in filling the insulating space.

Various other and ancillary objects and advantages of the invention will become apparent from the following description and explanation of the invention which is given in connection with the accompanying drawings in which:

Fig. 1 represents blowing apparatus as it may be employed to fill a box-like container;

Fig. 2 is a vertical cross-section in a perspective view of a carboy containing a bottle spaced from the walls of the carboy, the carboy being fitted with a substitute cover as a fixture for the present invention;

Fig. 3 is a perspective view of the fixture;

Fig. 4 is a vertical cross-section of the completed packed carboy;

Fig. 5 is a plan view of a refrigerator minus its door with the refrigerator cabinet lying horizontally on its back;

Fig. 6 represents a fixture to be placed over the cabinet shown in Fig. 5 when the breaker strip of said cabinet is not yet in place; and

Fig. 7 illustrates in plan view the cabinet of Fig. 5 with the fixture of Fig. 6 in place thereon.

In my earlier parent application Serial No. 294,212, the process is described generically and specifically with respect to various forms of the space to be filled, and various types of space-confining walls, and removable fixtures, having particular reference to variations in the process for insulating domestic-type refrigerators. These variations include filling a refrigerator in which the food compartment is already mounted, and also in which the food compartment is not mounted. In the latter case, a fixture in the form of a dummy for the food compartment is employed, and the fixture is used to provide filtering area, and may be used to provide inlet area. The process is flexible for accommodating it to various types of refrigerators, as well as various types of spaces not necessarily those of refrigerators. In the said earlier application there is claimed specifically a method of filling a refrigerator in which the food compartment is mounted, both the cabinet and the food compartment having openings therein for accommodating the insertion into the food compartment of a refrigerating unit. One of the said openings to the space is used for introducing the gas, while the other is blocked off. The open space at the door

opening between the cabinet and the food compartment, where breaker-strip material is located in the completed refrigerator, is closed by a fixture or closure provided with filtering area, and preferably including also some imperforate area. Thus, the gas introduced passes through the gas-filtering body of insulating material built up in the space. Then the fixture is removed, and breaker strip used to close the gap. The space between the openings for the unit thus has insulation, which may be disturbed as necessary in making connections when installing the refrigerating unit.

It is also set forth that the stream is introduced at a differential pressure between inlet and filter areas. This may be effected by having atmospheric pressure at either the inlet area, or at the filtering area. The latter is preferred for many practical and mechanical reasons.

In the present application it is likewise intended that the pressure be a differential one, but to simplify the description and the illustration, only the preferred one of super-atmospheric pressure at inlet area is specifically described and illustrated without intention to limit the invention thereto.

After the introduction of the insulating material into the space to be insulated, especially in a refrigerator, there are numerous mechanical operations which may be necessary to complete the article for use or sale. However, these form no essential part of the invention, and detailed description and illustration of them are herein omitted.

The preferred closures or other means having filtering area are preferably permanent fixtures used in a production line, and are in preferred practice removed after each use. However, these may be of other structure, for example, metal or cloth filters of such character that they need not be removed. When retained, they may be a permanent part of the final structure, covered or not. Hence, the removal of such closures is not considered an essential part of the process. But in certain cases it may be included as an essential part of certain aspects or variations of the invention.

The present invention may be used for fibers, flakes and particles of other forms. Examples of fibers are hair, wood fiber, vegetable fiber, kapok, mineral wool, glass wool, asbestos, straw, grasses and many others. Examples of other materials are flaked paper, exfoliated vermiculite, mica, ground cork and like materials. Fibers are preferred, because they mat and felt and produce stable forms in more complex variations of the invention where fixtures may be used and removed. The following illustrations are, therefore, given with respect to wood fiber, such as that according to my said copending application Serial No. 336,495, filed May 22, 1940, now Patent No. 2,325,055, issued July 7, 1943, which were developed primarily for use in the present invention.

The invention involves the building up of a consolidated gas-filtering body of particles of insulating material introduced as suspended matter in a stream of gas, into a confined space to be insulated; and it involves the provision in the confining walls of said space of filtering area to retain the particles and exhaust the gas. The location of inlet area, the number of inlet areas, and the location, size and number of filtering areas are not critical with respect to any given space. This is because the stream of gas is in-

roduced at a velocity to impel the particles with turbulence into the space and to all parts of the space. The greater the shortest distance from inlet area to filtering area, the thicker is the body of insulating material through which gas must pass to exhaust. Therefore, for practical convenience, it is desirable to have filtering area close to, or even adjacent to inlet area. Experience has shown that because of the turbulence the particles may deposit in regions some of which are adjacent to filtering area, and others of which are remote from both inlet area and filtering area. The resulting deposit grows toward the inlet area, and to or through the inlet area. In such case, the filtering area close to or adjacent inlet area facilitates the deposition of the last deposited material. The conditions establish a complexity of air currents which change as the remaining space to be filled changes. Cyclonic currents have been observed which tend to throw carried particles centrifugally out of the local air stream, and deposit them by centrifugal force and in the manner described. Also direct deposition by filtration has been observed as one of the resulting actions to deposit the introduced particles.

The preferred means for creating the moving stream of gas carrying suspended particles is illustrated in Fig. 1. A fan-type blower 45 has pipe 46 for the entry of air into which fiber may be fed by hand, or by a mechanical device, such as a picker, or a worm screw 46a. The fan discharges downwardly through conduit 47, to which suitable connection is made.

Consider the apparatus of Fig. 1 when the pipe 47 is 6 inches in diameter and connected to a space to be filled. The fan is operated at 3740 R. P. M. by a 15 H. P. motor of 1800 R. P. M. Running idle (connected and operated but no fiber fed), the measured pressures are as follows:

Table I

In pipe 47	Pressure in inches of water
Lateral (static) pressure.....	8.5
Total pressure.....	10.25
Velocity pressure.....	1.75
Velocity.....	5300 ft. per minute.
Output.....	1040 cu. ft. per minute.

The system shown in Fig. 1 has been used to fill a certain space $\frac{1}{4}$ full, then again to $\frac{1}{2}$ full, then to $\frac{3}{4}$ full, and then to 100% full, with measurements of the system (idle) at each stage. The measured values are combined in Table II with values taken from Table I and are in the same units as those in Table I.

Table II

Measured in pipe 47	Empty	$\frac{1}{4}$ full	$\frac{1}{2}$ full	$\frac{3}{4}$ full	Full
Static pressure.....	8.5	12	12	13.5	14.75
Total pressure.....	10.25	13	13	13.5	14.75
Velocity pressure.....	1.75	1	1	1	1
Velocity.....	5300	4006	4006	4006	4006
Output.....	1040	785	785	785	785

It is noted that under conditions where the exit is wholly or to a degree blocked, as when the space is full, there is a "back pressure" encountered at the inlet to the centrifugal fan.

The back-pressure is an important feature of the use of super-atmospheric pressure feed, with apparatus permitting back pressure. Consider in Fig. 1 that the fan may run while the feed line

47 is open. A momentum is established into pipe 47. As this is blocked off, the moving stream is retarded, at first in part, and fiber gradually fills up the inlet conduits. A window (later described) indicates this and the process may be stopped. If not stopped the back pressure at the inlet blows fiber back in pipe 46. Thus, fiber fed into the inlet will also be blown out the inlet. The appearance of back-feed or back-pressure is an indication of the final status of being filled.

Many factors influence the result, and practically, it is necessary to arrive at standard conditions for the particular equipment used, and the job at hand. For example, it has been found to be a general rule, that the faster the fiber is fed, the less the density of the mat obtained. However, this rule is limited to a very short period of time. In one tested instance, the feeding time for the space was varied from fractions of a minute to several minutes. The curve of density has been plotted vertically against feeding time plotted horizontally. The curve rises rapidly, and at about 25 seconds it begins to flatten out. In about 60 seconds it has reached a maximum density. Such curves were obtained with different fan speeds, and it was found that high speeds (greater kinetic energy to fiber) at the same feeding time gave higher density mats. By constructing such curves from experimental procedure, the conditions for most efficient operation and for uniform operation may be easily determined.

The space to be filled need not be of box-like or panel-like form. It may be more complex, and even be what is called "angular," that is, it has one or more regions between which and at least one inlet area to the confined space there is no connecting straight line lying wholly within the confined space, but rather there is at least one obstructing space-confining wall. This compels particles to flow to such a region by an indirect line, such as an angular line, the paths, however, being complex because of the turbulence within the space. The velocity of the stream of gas introduced and the location and size of filtering area relative to inlet area are all such that particles are carried with turbulence to all portions of the confined space.

Fig. 2 represents a carboy, such as employed for shipping acids, on a platform 58, there being a screen opening 59 in the bottom to retain particles, and to serve as filtering area when not obstructed (as shown) by platform 58. The carboy has a casing 60 of box-like form in the bottom of which, as at the corners, are spaced blocks 61 of spacing material, such as of cork or composition, or wood, but preferably of insulating material such as insulating fiber board. Blocks 61 space a bottle or flask 62 above the bottom 63 of the casing, providing space 64 beneath the bottle, and they also space the bottle from the sides 65 of the casing, thus providing a circuitous peripheral space 66. Usually the mouth 67 of such a bottle projects from a closed casing, as through a hole 68 in a cover 69, under a protecting bridge 70.

In accordance with the present invention, before such a cover 69 is applied, a temporary closure or fixture plate (Fig. 3) is fitted over the casing. As shown, this fixture has a body plate 71, a flange 72 to fit over the casing, and a hole 73 is provided with means to seal the hole to the neck of the bottle, such as an elastic sheet rubber ring 74. Area 75 in plate 71 represents inlet area, and it is covered by a hood 76, connected to or attachable to a conduit 77. Conduit 77 may be

connected to the blower of Fig. 8. A filtering area is provided in plate 71 by mounting therein wire screen 79.

Upon blowing air containing insulating particles, such as fiber, into casing 60, by means of the fixture in place over the casing, the fibers pack under and around the bottle and to the fixture, and to or into the hood 76. The fixture is then removed, and the cover (of Fig. 4) is secured in place.

As applied to refrigerator cabinets, the present invention is best employed with cabinets in which the food compartment is already mounted. Fig. 5 represents such, in plan view with a conventional cabinet 80 lying on its back. The cabinet has a door opening facing upwards. The cabinet shell, when of metal, has a peripheral internal flange 81, across the corners of which braces 82 are secured. A food compartment 83 is mounted inside the cabinet by means of an external flange 84 thereon, secured to said braces 82. This forms a space 85 around the food compartment, and under it (in the position shown) to receive insulation. In the back of the food compartment is illustrated a temporary plate 86 covering an opening for use in connection with a refrigerating unit later to be installed. The plate 86 aids in confining the space to be insulated, and if desired a screen 86a with an adjustable slide cover 86b may be located therein, for non-use of its filtering area, or for adjustment in area for use as filtering area. This is representative of any other filtering area, not in the fixture, which may be used. In preferred practice screen 86a is covered and not used. Where there is also an opening (not shown) in the cabinet opposite the said unit-opening in the food compartment, this also may be closed by a plate, but no plate is needed where a platform on which the back of the cabinet rests is imperforate to serve as a closure for such an opening. In the finished refrigerator, breaker-strip material, shown in fragmentary form at 87, covers the open space at the door opening, this being suitably secured as to the flanges 81 and 84. A cover plate is shown in part at 88, for the bottom front of the operating refrigerator, behind which operating machinery may be located.

The peripheral open space 85 at the door opening is covered by a temporary closure, or fixture, shown in Figs. 6 and 7. The closure comprises frame members 90 fitting over flange 84, and frame members 91 fitting over flange 81, with space between the frames. At the corners, this space may be rendered imperforate, by means 92 providing imperforate area in part confining space 85. Adjacent the said corner means 92 are screens 93 providing filtering area in part confining said space 85. Between the pairs of screens 93 on each panel side of the space 85, there is inlet area defined by the open ends of covering hoods 94 to 97, which are connected by conduits 98 to a common unit 99 into which the air stream is blown. Hoods 94 and 96 may be bifurcated internally as shown. Windows 100 permit seeing when fiber or the like packs into the hoods, indicating completion of the filling of space 85.

The fixture is then removed, and the breaker strip 87 is substituted therefor over the body of insulating material exposed on removing the fixture.

Wood fiber may be packed into the space at various densities, as from 2.0 to 4.5 pounds per cu. ft. to provide a mat resistant to settling by shock, the mat in such range having a K-value in the range from .20 to .27. However, it is to be

understood that changes in form of the insulating material and of operating conditions may bring the K-value out of this range. The packing by arresting moving fibers provides a high degree of felting, which is a factor indicating resistance to settling.

The use of a fan is preferred for the reason that it is a means of unfelting the fibers to substantially individual fibers. It is this form which 10 gives the best results. However, broadly, the fibers need not be completely unfelted, and may be in clusters or small aggregates. Use of other means, such as vacuum on the screen end, or feeding fiber directly into a current of air, is 15 conducive to providing such loose aggregates, rather than individual particles of fiber. The important point is that these are not under mechanical pressure to felt them, and they tend to unfelt in process.

20 The terms "screening means" and "filtering area" as used herein or in the claims refer to an area with any effective lattice or perforated member which acts as a screen to filter particles from the carrying gas, and it is to be distinguished 25 from a member porous to air and from a crack or an elongated slot.

Numerous modifications and uses of the invention are contemplated in the appended claims.

I claim:

- 30 1. In depositing particles of insulating material into the space defined and confined by walls including the walls of a refrigerator cabinet and of a food compartment mounted therein, and including removable closure means over said space at the door opening of the refrigerator, said closure means having a plurality of introductory inlets opening into said space including one to each panel-form space at the door opening, of which walls the space confining surfaces include a major portion which is substantially resistant to the passage of gas and one or more remaining portions, each in the form of screening means with foramina relatively minute compared with said one or more inlets, for venting gas from said space and for retaining said particles in the space, the method which comprises, suspending in a moving gas, particles of insulating material which pack to a consolidated body that is a gas-filtering body at an insulating density of the so-packed particles; introducing the resulting moving gaseous suspension into said space by conducting the suspension to and through said introductory inlets; simultaneously venting said gas from said space through said screening means, 40 and there filtering said vented gas from particles, thereby depositing and packing particles to form a growing gas-filtered mass thereof in corresponding portions of said space over and extending away from said screening means; simultaneously maintaining in the remaining portion of said space a condition of turbulence of said gaseous particle-suspension by maintaining a high and sufficient velocity therefor in introducing said suspension whereby the turbulence causes deposition 45 and packing of particles in margins of the turbulent space; continuing said introduction, said maintenance of turbulence, and said venting of said gas through said screening means, and also through said growing mass at least until a body of said particles begins to form in each of said inlets and said space is completely packed with said particles consolidated to a gas-filtering body at an insulating density and resultingly molded into said space and compressed therein 50 55 60 65 70 75 by the differential introduction pressure between

said inlets and said screening means; removing said closure means and retaining in situ the material packed into said space; and applying confining material over the open space left by removal of said closure means.

2. In depositing particles of insulating material into the space defined and confined by walls including the walls of a refrigerator cabinet and of a food compartment mounted therein, and including removable closure means over said space at the door opening of the refrigerator, said closure means having a plurality of introductory inlets opening into said space including one to each panel-form space at the door opening, of which walls the space confining surfaces include a major portion which is substantially resistant to the passage of gas and one or more remaining portions, each in the form of screening means with foramina relatively minute compared with said one or more inlets, for venting gas from said space and for retaining said particles in the space, of which screening means at least one is in said closure, the method which comprises, suspending in a moving gas, particles of insulating material which pack to a consolidated body that is a gas-filtering body at an insulating density of the so-packed particles; introducing the resulting moving gaseous suspension into said space by conducting the suspension to and through said introductory inlets; simultaneously venting said gas from said space through said screening means, and there filtering said vented gas from particles, thereby depositing and packing particles to form a growing gas-filtering mass thereof in corresponding portions of said space over and extending away from said screening means, simultaneously maintaining in the remaining portion of said space a condition of turbulence of said gaseous particle-suspension by maintaining a high and sufficient velocity therefor in introducing said suspension whereby the turbulence causes deposition and packing of particles in margins of the turbulent space; continuing said introduction, said maintenance of turbulence, and said venting of said gas through said screening means and also through said growing mass at least until a body of said particles begins to form in each of said inlets and said space is completely packed with said particles consolidated to a gas-filtering body at an insulating density and resultingly molded into said space and compressed therein by the differential introduction pressure between said inlets and said screening means; removing said closure means and retaining in situ the material packed into said space; and applying a confining material over the open space left by removal of said closure means.

3. In depositing particles of insulating material into the space defined and confined by walls including the walls of a refrigerator cabinet and of a food compartment mounted therein, and including removable closure means over said space at the door opening of the refrigerator, said closure means having a plurality of introductory inlets opening into said space including one to each panel-form space at the door opening, of which walls the space confining surfaces include a major portion which is substantially resistant to the passage of gas and one or more remaining portions located in said closure means, each in the form of screening means with foramina relatively minute compared with said one or more inlets, for venting gas from said space and for retaining said particles in the space, the method which comprises, suspending in a moving gas,

particles of insulating material which pack to a consolidated body that is a gas-filtering body at an insulating density of the so-packed particles; introducing the resulting moving gaseous suspension into said space by conducting the suspension to and through said introductory inlets; simultaneously venting said gas from said space through said screening means, and there filtering said vented gas from particles, thereby depositing and packing particles to form a growing gas-filtering mass thereof in corresponding portions of said space over and extending away from said screening means, simultaneously maintaining in the remaining portion of said space a condition of turbulence of said gaseous particle-suspension by maintaining a high and sufficient velocity therefor in introducing said suspension whereby the turbulence causes deposition and packing of particles in margins of the turbulent space; continuing said introduction, said maintenance of turbulence, and said venting of said gas through said screening means and also through said growing mass at least until a body of said particles begins to form in each of said inlets and said space is completely packed with said particles consolidated to a gas-filtering body at an insulating density and resultingly molded into said space and compressed therein by the differential introduction pressure between said inlets and said screening means; removing said closure means and retaining in situ the material packed into said space; and applying a confining material over the open space left by removal of said closure means.

4. In depositing particles of insulating material into the space defined and confined by walls including the rectangular walls of a refrigerator cabinet and of a rectangular food compartment mounted therein and including a removable closure over a rectangular space peripheral to the food compartment at the door opening of the refrigerator, said closure having four spaced introductory inlets opening into said peripheral space, of which walls the space confining surfaces include a major portion which is substantially resistant to the passage of gas and one or more remaining portions, each in the form of screening means with foramina relatively minute compared with said four inlets, for venting gas from said space and for retaining said particles in the space, including screening means in said closure, the method which comprises, suspending in a moving gas particles of insulating material which pack to a consolidated body that is a gas-filtering body at an insulating density of the so-packed particles; introducing the resulting moving gaseous suspension into said space by conducting the suspension to and through said four introductory inlets; simultaneously venting said gas from said space through said screening means, and there filtering said vented gas from particles, thereby depositing and packing particles to form a growing gas-filtering mass thereof in corresponding portions of said space over and extending away from said screening means; simultaneously maintaining in the remaining portion of said space a condition of turbulence of said gaseous particle-suspension by maintaining a high and sufficient velocity therefor in introducing said suspension whereby the turbulence causes deposition and packing of particles in margins of the turbulent space; continuing said introduction, said maintenance of turbulence, and said venting of said gas through

said screening means and also through said growing mass at least until a body of said particles begins to form in each of said four inlets and said space is completely packed with said particles consolidated to a gas-filtering body at an insulating density and resultingly molded into said space and compressed therein by the differential introduction pressure between said inlets and said screening means; removing said closure and retaining in situ the material packed into said space; and applying a confining material over the peripheral space left by removal of said closure.
